UNITED STATES PATENT OFFICE.

ROBERT C. DANLY, OF CHICAGO, ILLINOIS.

MAGNETO

1,214,015.

Specification of Letters Patent. Patented Jan. 30, 1917.

Application filed June 28, 1915. Serial No. 36,683.

To all whom it may concern:

Be it known that I, ROBERT C. DANLY, a citizen of the United States, residing at Chicago, in the county of Cook and State of Illinois, have invented certain new and useful Improvements in Magnetos, of which the following is a specification.

My invention relates to electro-magnetos for use in connection with internal combustion engines wherein the charge of combustible fluid is ignited by means of an electric spark produced at recurring intervals by means of an electric current generated by a magneto deriving motion from a moving part of the engine mechanism and suitably connected with the ignition mechanism.

The object of my invention is to provide improved means whereby the magneto may be mounted upon the engine and connected with the ignition mechanism, and means separable from the magneto for imparting an oscillating movement thereof in opposite directions, said means being carried by a base member mounted upon a bracket, preferably integral with a flange member forming a part of a block having movable and fixed electrodes mounted therein, and secured to the cylinder head of an engine, the operative mechanism permitting a disconnection of the magneto from the ignition mechanism if for any reason battery current is desired, and transmitting motion to the rotor in a manner to eliminate any strains in a direction tending to cause the rotor to move bodily toward the poles of the field magnet and thus break the air gap between the armature and poles and thereby destroy the efficiency of the magneto. These objects are attained by means of the mechanism illustrated in the accompanying drawings, in which—

Figure 1 is a side elevation of part of an engine cylinder carrying an igniter mechanism having my improved magneto connected therewith; Fig. 2 is a top plan view of a bracket member supported by the igniter block and having the rotor actuating mechanism mounted thereon; Fig. 3 is an end elevation of Fig. 1; and Fig. 4 is a cross section of Fig. 1 along line A—B.

Referring to the drawings, wherein the same reference numerals designate like parts throughout the several views, 1 represents part of an engine cylinder, including a cylinder head 2, having an opening therein that receives a cylindrical block 3, having a

flange 4 whereby the block is secured to the head by means of stud bolts 5.

6 represents an outwardly extending L-shaped arm, preferably integral with the flange 4 and having secured thereto a plate member 7 by means of bolts 8 and supported by the block 3 in substantially the same manner as is shown in Patent No. 820,585, May 15, 1906, G. J. Weber.

9 represents a rock shaft disposed parallel with the block 3 and journaled in bearings 10 forming part of the plate 7, and having oppositely disposed arms 11 at one end thereof. The arms are provided at their free ends with fork members 12 spaced apart and receiving between them rollers 13 provided with annular grooves, one of said rollers being mounted upon a cross pin 14 and the remaining roller upon a stud 15 having a collar 16 engaging with one of the fork members and a securing nut 17 with the coacting fork member, the stud extending beyond the collar, and 18 represents a connecting link having one end journaled upon the extension of the stud.

19 represents laterally extending arms integral with the plate 7 and disposed upon opposite sides of the axis of the shaft 9 and in the same horizontal plane, and carrying 85 at their free ends studs 20 disposed parallel with the axis of the shaft and having mounted thereon rollers 21 in line with and like in form to those designated by 13, and 22 represents tension springs having their opposite ends connected with the rollers and operative to normally resist an oscillating movement of the shaft 9 in a well-known way. Secured to the opposite end of the shaft 9 is a common form of trip arm 23 95 adapted to engage with a reciprocatory member 24 forming part of the igniter actuating mechanism.

The igniter mechanism includes a fixed electrode 25 and an oscillating electrode 26 100 carried by the block 3 in a common way, and 27 represents a coiled torsional spring operative in a direction to normally hold the arm 28 at the inner end of the movable electrode in contact with the fixed electrode.

29 represents an arm carried by the opposite end of the movable electrode and having at its free end an adjustable screw 30 that is secured in adjusted position by means of a locking nut 31, the screw being adapted 110 to engage intermittently with an arm 32, preferably integral with the trip arm 23.

33 represents a magneto detachably secured to the plate 7, including field magnets 34 secured to a frame 35, in which is journaled a rotor 36, having an arm 37 secured to one end thereof, the free end of the arm being operatively connected with the opposite end of the connecting link 18, whereby motion is transmitted to the oscillatory rotor from the rock shaft 9 when it is actuated by the reciprocating member 24 engaging with the arm 23, and 38 represents a current transmitting connection between an insulated plug 39 on the magneto and the fixed electrode.

15 In operation the shaft 9 is oscillated by means of the bar 24, against the tension of the springs 22, that react to return the shaft to its initial position, and a tendency of the springs, in resisting a throw of the arm 23, to rock the shaft 9 in a distorted axial alignment is not transmitted to the rotor of the magneto, thereby permitting a free axial angular movement thereof, and a minimum air gap between the periphery of the rotor 25 and the pole pieces of the magnet.

Having shown and described a preferred embodiment of my invention, it is understood that changes may be made in the specific details of its construction and in the 30 form and proportion of its various parts without departing from the spirit of the invention as indicated in the appended claims.

40 represents a cam disk integral with the shaft 9 intermediate the arms 11, and provided with a shoulder portion 41 adapted to engage with a cocking latch 42 pivoted upon the plate 7 between depending ear members 43, and 44 represents a plate spring interposed between the upper side of the latch 40 and the bottom of the plate and operative to frictionally resist an angular movement of the latch in opposite directions. It is desirable to have the cocking latch carried by the bracket having the magneto, the electrode 45 carrying block and other operative parts forming a unitary structure that may be readily detached from the engine cylinder for the purpose of testing the efficiency of the magneto in causing a satisfactory spark.

50 What I claim as my invention, and desire to secure by Letters Patent, is:

1. A magneto including, in combination, a rotor, an arm on said rotor a rock shaft journaled parallel and in the same vertical plane with said rotor, an arm on one end of said rock shaft, a link connection between said arms, an arm upon the opposite end of said rock-shaft and means engaging with said third arm for actuating said rock shaft 55 intermittently in one direction from a moving part of an engine, and spring means, operable to return said shaft to its initial position.

2. A magneto including, in combination, a 60 frame, a rotor journaled in said frame, an

arm on said rotor, a supporting base having said frame secured thereto, a rock shaft journaled in said base parallel with and in the same vertical plane with said rotor, an arm on said rock shaft, a link connection between said arms, an arm upon the opposite end of said rock-shaft and means engaging with said third arm intermittently for actuating said rock shaft in one direction from a moving part of an engine, and spring means 70 operable to return said shaft to its initial position. 75

3. A magneto including, in combination, a frame, a rotor journaled in said frame, an arm on said rotor, a separable supporting base, means for securing said frame to said base, a rock shaft journaled in said base, an arm on said rock shaft, a link connection between said arms, means for actuating said rock shaft in one direction from a moving 80 part of an engine, and spring means operable to return said shaft to its initial position. 85

4. A magneto including, in combination, a frame, a rotor journaled in said frame, an arm on said rotor, a separable supporting base, means for securing said frame to said base, a rock shaft journaled in said base, oppositely disposed arms upon one end of said rock shaft, a tripping arm upon the opposite 90 end of said shaft, oppositely disposed fixed arms carried by said base, tension springs connecting said fixed arms with the arms upon said shaft, a link connection between the arm on said rotor and one of the arms on 95 said rock shaft, and means operable from a moving part of an engine and adapted to engage intermittently with said tripping arm. 100

5. An ignition mechanism for internal combustion engines including, in combination, an igniter block, fixed and movable electrodes carried by said block, a bracket member supported by said block, a rock shaft journaled in said bracket; a trip arm on said rock shaft, an arm on said movable 105 electrode adapted to engage with said trip arm, a spring tending to hold said arms in engagement, a magneto carried by said bracket, said magneto including an oscillatory rotor, and motion transmitting means 110 connecting said rotor with said rock shaft. 115

6. A magneto including, in combination, a frame, a rotor journaled in said frame, an arm on said rotor, a separable supporting base, means for securing said frame to said base, a rock shaft journaled in said base, oppositely disposed arms upon one end of said rock shaft, a tripping arm upon the opposite end of said shaft, oppositely disposed fixed arms carried by said base, tension 120 springs connecting said fixed arms with the arms upon said shaft, a link connection between the arm on said rotor and one of the arms on said rock shaft, means operable from a moving part of an engine and adapt- 125

130

- ed to engage intermittently with said tripping arm, an igniter block carrying said supporting base, a rocking electrode journaled in said block, an arm on said electrode, 5 an arm on said rock shaft adapted to intermittently engage with said electrode arm, and a spring tending to hold said arms in engagement.
7. A magneto including, in combination, a 10 frame, a rotor journaled in said frame, an arm on said rotor, a separable supporting base, means for securing said frame to said base, a rock-shaft journaled in said base, oppositely disposed arms upon one end of said 15 rock-shaft, a tripping arm upon the opposite end of said shaft, oppositely disposed fixed arms carried by said base, tension springs connecting said fixed arms with the arms upon said shaft, a link connection between the arm on said rotor and one of the arms 20 on said rock-shaft, means operable from a moving part of an engine and adapted to engage intermittently with said tripping arm, and a rotor cocking mechanism including a notched disk carried by said rock-shaft and 25 a cocking latch pivoted upon said base and adapted to releasably engage with said notched disk.

R. C. DANLY.
